UNITED STATES PATENT OFFICE.

JOSEPH MCGRATH, OF NEWTON, KANSAS.

SOFA-BEDSTEAD.

SPECIFICATION forming part of Letters Patent No. 293,488, dated February 12, 1884.

Application filed August 28, 1883. (Model.)

To all whom it may concern:

Be it known that I, JOSEPH MCGRATH, of Newton, in the county of Harvey and State of Kansas, have invented a new and Improved 5 Sofa-Bedstead, of which the following is a full, clear, and exact description.

The object of my invention is to provide a new and improved hinge for hinging the removable seat or top of a sofa-bed, lounge, extensible chair, or other like piece of furniture to the seat-frame.

Reference is to be had to the accompanying drawings, forming part of this specification, in which similar letters of reference indicate corresponding parts in all the figures.

Figure 1 is a cross-sectional elevation on the line *x x*, Fig. 2, of a sofa-bed provided with my improved hinge, showing the seat on the seat-frame. Fig. 2 is a front view, showing it 20 in a like position. Fig. 3 is a cross-sectional elevation of the same on the line *y y*, Fig. 2, showing the top swung down. Fig. 4 is a plan view of the joint.

A metal band, A, is secured to the back B 25 and to the top of the seat-frame C of a sofa, lounge, or chair, and terminates in an eye, D, at the front edge of the seat-frame. A bracket, E, or stud, or other equivalent, projects from the band A or from the front face of the back. 30 The band A can be secured on the front or rear side of the back B.

To the front eye, D, of the band A an angularly-bent metal bar, F, is hinged, which is at the side of the band A. The said bar F is 35 provided at its inner end with a projecting arm, G, to the free end of which a spiral or like acting spring, H, is fastened, the other end of which is fastened to one of the legs of the sofa, lounge, &c.

To the end of the front shank of the angular bar F a band, or bar, J, is hinged, which is fastened to the under side of the removable seat or removable top K, the joint of the bar F and band J being at about the middle of 45 the width of the seat, and the band J being at the same side of the bar F as the band A, as is shown in Fig. 2. A spring, L, is fastened to the bottom of the seat-frame C in such a manner that it can act on the free end of the

arm G. The seat K is provided with downwardly-projecting legs M at the front edge, and a front board, N, fitting between the legs M, is secured to the inner shanks of the angular bars F.

When the bed is folded, the free end of the under side of the seat K rests on the brackets E, and the angle-bars F are drawn upward, so that the front plate, N, will be between the legs M, which may rest on the top of the front part of the seat-frame, as shown in Figs. 1 and 2.

If the sofa is to be used as a bed, &c., the seat is pulled toward the front and downward until its legs M rest on the floor, the angular bars F and the plate N swinging downward, as shown in Fig. 3. The springs H and L 65 counterbalance the swinging part and greatly facilitate the raising of the seat upon the seat-frame, as both springs press or draw the free end of the arms G downward, thereby tending to throw the angular bars F and the seat-frame 70 upward.

It will be observed that when the seat is on the seat-frame the outer shanks of the angular bars F rest against the under side of the seat K.

My improved hinge can be used on any sofa, 75 lounge, easy-chair, and like piece of furniture.

Having thus described my invention, I claim as new and desire to secure by Letters Patent—

1. The combination, with a metallic band, A, a sofa-seat frame, C, and a back having 80 the projections E, of the metallic angular bar F, hinged to an eye, D, of said band, the bar J, hinged to bar F, and the removable seat K, the latter being provided with downwardly-projecting legs M, and a front board, N, secured between said legs to the inner shank of bar F, as shown and described.

2. The combination, with a seat-frame, C, having a back, B, of the bands A, the brackets E, the angularly-bent bars F, the removable seat K, and the bands J, secured to the under side of the same, the angular bars F being hinged to the bands A and J, substantially as herein shown and described.

JOSEPH MCGRATH.
